UNITED STATES PATENT OFFICE.

HANS OTTO SWOBODA, OF NEW YORK, AND ERWIN LAVENS, OF BROOKLYN, NEW YORK, ASSIGNEES TO THE GENERAL INCANDESCENT ARC LIGHT COMPANY, OF NEW YORK.

ELECTRIC-ARC LAMP.

SPECIFICATION forming part of Letters Patent No. 553,697, dated January 28, 1896.

Application filed September 6, 1894. Serial No. 522,290. (No model.)

To all whom it may concern:

Be it known that we, HANS OTTO SWOBODA, of the city and county of New York, and ERWIN LAVENS, of Brooklyn, Kings county, 5 State of New York, have invented a certain new and useful Improvement in Arc Electric Lamps, of which the following is a specification.

We will describe a lamp embodying our improvement, and then point out the novel features in the claims.

In the accompanying drawings, Figure 1 is a sectional side elevation of a lamp embodying our improvement. Fig. 2 is a side elevation of certain parts of the lamp in normal position. Fig. 3 is a similar view of the same parts in the position which they occupy during the feeding of the carbon. Fig. 4 is a sectional elevation in a plane at right angles 10 to Fig. 1, certain parts being broken away. Fig. 5 is an inverted plan of certain parts providing for the suspension of the lamp.

Similar letters of reference designate corresponding parts in all the figures.

25 A designates the frame of the lamp. It may be of any suitable form and construction, and the circuit may be extended either through or along it in any approved manner. In the present instance this frame comprises 30 a rod a, which is suspended from a cap B, the latter being constructed to be secured permanently to any suitable overhead support.

35 C' C² designate the upper and lower carbons. In the present instance the lower carbon, C', is secured in an immovable carbon-holder D', and the upper carbon, C², is secured in a holder D², which is movable, for the purpose of feeding this carbon as well as 40 for establishing the arc.

We have shown the upper-carbon holder D² as secured to a rod E, which is provided with a toothed rack e; but any equivalent for this rack-bar may be used. For instance, 45 a band, chain, or any other flexible material combined with a pulley or pulleys may be employed. Whatever the character of this support E shall be the same mechanism may serve to control it.

50 With the rack e of the bar E engages a pin-

ion E' mounted loosely upon a shaft E². This shaft E² forms one of the stretchers or cross-pieces of a frame F comprising, as here shown, triangular side pieces as well as suitable cross-pieces or stretchers. The shaft E² 55 is shown as having its ends shouldered and screw-threaded beyond the shoulders, so as to fit the side pieces of the said frame F and receive outside the side pieces nuts for clamping the side pieces and shaft together. The 60 extremities of the shaft may be provided with conical recesses to receive the ends of conical screws engaging with tapped holes in the side pieces of a frame G and clamped to these side pieces by means of suitable nuts. 65

The frame G is a fixture in the frame of the lamp, but the frame F rocks upon the axis of the shaft E².

E³ designates a ratchet-wheel which is affixed to the pinion E' and with it is capable 70 of turning loosely upon the shaft E². With this ratchet-wheel E³ engages a pawl E⁴, that is mounted upon a gear-wheel E⁵ in engagement with the ratchet-wheel by a spring E⁶ affixed to the wheel E⁵. The wheel E⁵ is 75 loosely mounted upon the shaft E² and is unconnected with the pinion E' and ratchet-wheel E³. Hence the support E of the upper carbon may be raised without causing any rotation of the gear-wheel E⁵; but when the 80 said support E is lowered it will cause a rotation of the gear-wheel E⁵. The gear-wheel E⁵ engages with a pinion E⁶, which is affixed to a shaft E⁷ that is journaled in the side pieces of the frame F. Upon the same shaft E⁷ is 85 affixed a brake-wheel E⁸. This brake-wheel therefore controls the descent of the support E for the upper carbon and consequently the feeding of the upper carbon.

E⁹ designates a brake-band fastened at one 90 end to a bracket f extending from one of the side pieces of the frame F and passing thence around the brake-wheel and secured at its other end to a rocking arm e² extending from a rock-shaft E¹⁰. (Here shown as made in 95 tubular form and mounted upon one of the cross-pieces or stretchers of the frame F.) The rock-shaft E¹⁰ is provided with an arm e³, which extends down one side of the frame F into a position opposite a stop g mounted 100

upon one of the side pieces of the frame G and made, as here shown, in the form of an adjustable screw so that its position may be varied to alter its action upon the rock-shaft 5 E¹⁰ and consequently upon the brake-band E⁹. When the frame F is rocked into such position that the arm e² controlling the brake contacts with the stop g of the frame G, then the brake will be released. The movement 10 of the frame F in the reverse direction will move the arm e² beyond the stop g and allow a spring E¹¹ to apply the brake again. This spring E¹¹ in the present instance is made of helical form and is connected at one end with 15 the arm e² and at the other with a bracket f² secured to one of the side pieces of the frame F.

II designates an electromagnet mounted in the frame G and coacting with an armature 20 II', which is affixed to the frame F. The movement of this armature toward the poles of the magnet is limited by means of a lateral projection f³ affixed to one of the side pieces of the frame F and coacting with a lateral 25 projection g² affixed to one of the side pieces of the frame G. Its movement in the other direction may be limited by a lateral projection g² affixed to the same side piece of the frame G and in such a position that when the 30 frame F moves in a direction to lower the armature away from the magnet the projection f³ of such frame will coact with said projection g². The armature is provided with a weight h, which as here shown is made in the 35 form of a nut adjustable upon a screw toward and from the axis of motion of the frame F along a screw h' extending from a bracket h² mounted upon the armature II'. Of course there may be any number of 40 weights made in the form of nuts applied to the screw. The weight or weights used will be adjusted to secure the proper conditions in a lamp.

It will be understood that whenever the 45 electromagnet attracts the armature sufficiently, it will rock the frame F so as to cause the release of the brake, so as to permit of the descent of the upper carbon, and that whenever the armature is released the frame 50 F will tilt forward so that the brake will be applied and the carbon-support E will be raised properly to establish the arc.

As in the present example of our improvement a plain shunt-wound electromagnet is 55 contemplated, we have shown a shunt cut-out as included in the lamp, but as this forms no part of our invention we do not deem any description of it necessary.

Obviously it will be within the spirit of 60 our invention to operate both ends of the brake-band instead of one side.

Turning now to the means for suspending the lamp, it will be seen that the cap B is provided internally with a ring b having a central opening, and that from its bottom extend 65 upward flanges b' b², which are made in the form of arcs of a circle large enough to enclose the rod a of the lamp-frame A. In the upper part of the rod a is a cross-pin a'. The flanges b' b² are so far separated at their ends 70 that this cross-pin a' may pass between them when the rod a is turned into the proper position. In the tops of the flanges b' b² are notches b³, and from these notches to one end of each of the flanges extend plain horizontal 75 surfaces b⁴, while from the notches toward the other end of each of the flanges extend inclined surfaces b⁵, that terminate in upwardly-extending projections or stops b⁶.

It will be readily understood that the rod 80 a may be engaged with the cap B by turning the rod a of the lamp-frame to such a position that its cross-pin a' will be opposite the space between the flanges b' b² and then raising the rod until the cross-pin shall have been elevated above the surfaces b⁴, if afterward the rod shall be rotated so as to bring the ends of the cross-pin a' opposite the notches b³. To disengage the pin a' it will be only necessary to rotate the rod a of the lamp-frame A in 85 the reverse direction until the pin a' is brought opposite the space between the flanges b' b², whereupon said rod a may be lowered from the cap B.

We have shown that a hood or reflector may 90 be attached to the inside of the ring b.

What we claim as our invention, and desire to secure by Letters Patent, is—

1. In an electric lamp, the combination of a movable frame, a brake and brake wheel 100 carried by said movable frame, a rock shaft provided with an arm also carried by said frame, a stop for coacting with said arm, and an adjustable weight or weights secured to the movable frame, substantially as specified. 105

2. In an electric lamp, the combination with a rod or tube a, provided with a projection or pin, and the cap B, of a receptacle provided with a flange or flanges having a notch or notches through which said pin may be 110 passed and subsequently caused to engage with the flange or flanges, substantially as specified.

In testimony whereof we have signed our names to this specification in the presence of 115 two subscribing witnesses.

HANS OTTO SWOBODA.
ERWIN LAVENS.
